UNITED STATES PATENT OFFICE

2,631,830

AIR CONDITIONING APPARATUS

Thomas W. Carraway, Dallas, Tex.

Application March 17, 1949, Serial No. 81,880

2 Claims. (Cl. 261—28)

1

This invention relates to air conditioning apparatus and more particularly to apparatus for conditioning, e. g. cooling, air by evaporation of a liquid.

In its general nature an apparatus constructed in accordance with the invention is arranged or equipped to be easily portable so as to be well adapted for "spot" cooling, that is for being moved from place to place to cool or condition limited areas or regions. The apparatus includes a casing which preferably is sectionalized or formed of interfitting sections to facilitate its assembly and to render its production economical. In the preferred form the bottom of the casing houses equipment for holding or supplying and dispersing evaporative liquid, e. g. water, in a finely divided or mist-like form in the intermediate and upper portions of the casing. Air is introduced into the casing above the liquid dispersing equipment and is drawn upwardly through the casing by a fan and discharged at or adjacent to the top of the casing after having been cooled by contact with and evaporation of the dispersed liquid.

An object of the invention is to provide an improved air conditioning apparatus having a novel construction and operating characteristics which render the apparatus especially suitable for cooling selected small or limited regions, particularly in dwellings.

Another object of the invention is to provide apparatus of the character referred to which, although of economical construction, is compact, having regard to its cooling capacity, and is of neat appearance rendering it suitable for use in nicely furnished rooms.

Another object of the invention is to provide an evaporative liquid type air cooling apparatus including improved equipment for supplying and dispersing liquid in finely divided or mist-like form in an air stream.

A further object of the invention is to provide an easily portable air conditioning unit.

Other objects of the invention will become apparent from a reading of the following description, the appended claims, and the accompanying drawings, in which:

Figure 1 is a central vertical sectional view of an air conditioning unit embodying the invention;

Figure 2 is a horizontal section on the line 2—2 of Figure 1, drawn on an enlarged scale;

Figure 3 is a fragmentary vertical sectional view on the line 3—3 of Figure 2;

Figure 4 is a detail fragmentary elevational

2

view of an intermediate casing section shown in Figure 2;

Figure 5 is a detail view, partly in elevation and partly in section, showing liquid dispersing equipment;

Figure 6 is a top plan view of the construction shown in Figure 5;

Figure 7 is a bottom plan view of a dispersing disk, a shaft being shown in section;

Figure 8 is an enlarged elevational view of a retractable caster and leg equipment;

Figure 9 is a vertical section on the line 9—9 of Figure 8;

Figure 10 is a fragmentary vertical sectional view of part of an evaporative liquid service tank and associated float operated valve;

Figure 11 is a vertical sectional view of a modified casing cover; and

Figure 12 is a top plan view of the cover shown in Figure 11.

The portable air conditioning unit shown by way of example in Figures 1 to 10 inclusive comprises a sectional casing generally designated A, provided with air inlet openings 1, air outlet openings 2 above the inlet openings, and a fan B for drawing air through the openings 1 into the casing, then upwardly in the casing, and then discharging the air outwardly through the openings 2 adjacent the top of the casing. Equipment designated C mounted in the bottom part of the casing serves to disperse or diffuse evaporative liquid, e. g. water, in the air stream flowing through the casing so as to cool the air by evaporation.

The casing is constructed in three sections, namely, a bottom section 3, an intermediate section 4, and a top section 5, which are so constructed that they may easily be assembled and secured together to provide a casing which has clean, uninterrupted outer lines and which is of neat appearance rendering the unit especially suited for use in homes. The bottom section 3 is provided with three caster supports 6 which may extend over or overlap the intermediate section 4. The upper parts of the supports 6 are connected to the bottom and intermediate sections 3 and 4 by bolts 7—7; and the bottom portions of the caster supports 6 are connected to the lower part of the bottom section 3 by bolts 8.

The intermediate section 4 is formed with an inwardly offset, downward extending flange 9 which fits snugly within the upper part of the bottom section 3. The shoulder on the intermediate section 4 surrounding the upper part of the flange 9 rests or fits upon the top edge of the

bottom section 3 as shown in Figures 1 and 9. By virtue of this construction, the sections 3 and 4 may easily be assembled and an uninterrupted smooth outer surface is provided.

The top section 5 is formed at its lower end with an inwardly offset, downwardly extending flange 10 which fits in the upper part of the intermediate section 4, and has a shoulder surrounding the upper part of the flange 10 and resting or fitting on the top edge of the intermediate section 4, the joint between the intermediate and top sections being similar to the joint between the bottom and intermediate sections. Bolts 11 may be provided for securing the assembled intermediate and top sections in place.

The top section 5 also is formed at its upper end with an inwardly offset, upwardly extending flange 12 which receives or fits inside of the vertical circumferential wall part 13 of a dome-shaped cover 14, the lower edge of the cover wall 13 resting or fitting upon the shoulder surrounding the bottom part of the flange 12.

The sectionalized construction of the casing A facilitates manufacture and assembly, and therefore permits economical production, in addition to providing a construction which is of neat appearance, well suited for use in living-rooms or other parts of domestic dwellings. The provision of the caster mountings 6, to be described more particularly hereinafter, makes it possible to move the unit easily to different locations where limited or "spot" cooling is desired.

The bottom casing section 3 serves to mount and enclose the equipment C for dispersing or diffusing evaporative liquid in the air stream passing through the casing. As shown in Figure 1, the bottom section 3 is provided with a bottom wall 15 which, in connection with the side walls of the section 3, provides or forms a main reservoir or supply tank 16. Mounted in the tank 16 is a smaller service tank 17, which is constantly supplied with liquid from the main reservoir 16. The tank 17 includes a tube 18 extending vertically and axially with respect to the casing A. A motor 19, supported underneath the bottom wall 15 by a hanger 20, has a shaft 21 extending upwardly through the tube 18. The shaft 21 supports and serves to rotate equipment for lifting liquid from the service tank 17, and throwing it upwardly and outwardly to disperse it in the air stream to produce the desired evaporative cooling of the air.

In accordance with the invention, the liquid-lifting equipment includes an inverted frusto-conical member or receptacle 22 having a central sleeve part 23 secured to the shaft 21 by means such as a set screw 24. A liquid tight seal 25 is interposed between the lower end of the central sleeve part 23 and the stationary tube 18. A sealed ball-bearing assembly 26 is interposed between the upper end of the tube 18 and the sleeve part 23 of the frusto-conical member 22. The outer or inclined wall part of the member 22 is formed with openings 27 for permitting liquid in the service tank 17 to enter the frusto-conical member, so that when the latter is rotated the liquid will be lifted and thrown upwardly by lifter vanes 28 which extend spirally around the axis of the frusto-conical member and diverge outwardly from bottom to top as best shown in Figure 5. Preferably the vanes 28 are each formed along its outer edge with a rib 28a.

In order more effectively to distribute or diffuse the evaporative liquid throughout the air stream, a target disk 29 is mounted on the upper end of

the shaft 21, being secured to the shaft in any suitable manner, for example by a set screw 29a. The disk 29 is formed with an inner circular groove 30, and is provided with a series of slots 31 or apertures 31 which extend from the root of the groove 30 at an inclination so as to open upwardly and outwardly at the top surface of the disk. The disk also is formed with an outer circular groove 32 which is concentric with the groove 30. A series of radial slots 33 extend from the groove 32 outwardly to the periphery of the disk 29. The service tank 17 is fitted with a plurality of division walls or baffles 17a, the inner edges of which are spaced from the member 22 sufficiently to provide operating clearance. The walls 17a prevent the liquid in the tank 17 from being whirled to form a vortex and spilling into the tank 16.

In operation, when the frusto-conical member 22 and the disk 29 are rotated, evaporative liquid is picked up and thrown off by the member 22 so that part of the liquid will be thrown upwardly and outwardly beyond the periphery of the disk 29, and the remainder of the liquid will be thrown against the disk. Some of the liquid which impinges upon the disk 29 will be thrown substantially radially outwardly by centrifugal force, and some of the liquid will enter the grooves 30 and 32. Liquid entering the groove 30 will flow through the inclined slots 31 so as to be thrown centrifugally upwardly and outwardly above the disk 29. Liquid will flow from the groove 32 radially outwardly through the slots 33 so as to collide, so to speak, with liquid thrown upwardly and outwardly from the top edge of the member 22. In this manner, substantially the entire cross sectional area of the casing A, except for its extreme outer portion, is filled with finely atomized, diffused, or dispersed evaporative liquid approximating a fog or mist which results in efficient evaporative cooling of the air passing through the casing.

Referring to the construction of the intermediate casing section 4, the inlet openings 4 are preferably formed by providing a series of vertical slits in the outer wall and then turning parts of the wall adjacent the slits inwardly to provide stiffening flanges 34. Mounted within the intermediate section 4 and above the inlet openings 4 is a throat member 35 which diverges from the casing axis from bottom to top as shown in Figures 1 and 3. The throat member 35 is connected at its top edge and in any suitable manner to the casing section 4, and at its bottom is formed with a flange 36 to which is secured the top ring 37 of a baffle structure generally designated 38. The baffle structure comprises a series of vertically extending baffles 39, connected at their tops to the ring 37 and connected at their bottoms to a ring 40. Each baffle 39 is L-shaped in horizontal section and, as shown in Figures 2 and 3, includes a long part 39a which is chordal with respect to the casing, and a short part 39b which extends at an angle to the long part 39a. The long parts 39a are so positioned as to diverge from each other from their inner to their outer edges, as shown in Figure 2. In operation, the baffles 39 prevent liquid dispersed by the equipment C from being thrown outwardly through the air inlet openings 4. Any liquid which is intercepted by the baffles and is not evaporated by the incoming air will drain back into the main reservoir 16.

Preferably, the intermediate section 4 is also

provided, above the throat 35, with a reticulated mat structure which may serve as a filter for removing dust from the air, but which principally provides a zone of multitudinous, minute air passages through which the air passes in contact with moistened fibrous material so as to effect a supplemental evaporative cooling, augmenting the cooling effected in the region or zone of liquid dispersal. The mat structure also serves to prevent stray unevaporated drops of liquid from being blown outwardly through the discharge openings 2. In the construction shown, the top of the throat member 35 is formed with an inwardly extending flange 41 which serves as a support for the outer ring 42 of a reticulated mat 43. A spacer ring 44, resting upon the outer ring 42, serves to support the outer ring 45 of another reticulated mat 46.

A ring 47, secured inside the top casing section 5 and surrounding the fan B, provides a slightly restricted passage for air flow. The outlet openings 2 in the top casing section 5 are immediately above the ring 47 and may be formed in the same manner as that in which the inlet openings 1 are formed in the intermediate casing section 4.

A motor 49 for driving the fan B is supported on top of an inverted frusto-conical member 50 which is formed with an upwardly extending flange 51 fitted inside of and secured to the flange 12 at the upper end of the top section 5. The motor shaft extends downwardly through a sleeve 52 for connection to the fan B. Thus the motor 49 is recessed, so to speak, in the upper end of the casing A, and is obscured from view by the dome-shaped cover 14.

Optimum operation of the equipment C can be obtained only by maintaining the evaporative liquid at the proper level in the service tank 17. For accomplishing this purpose the flow of liquid from the main storage tank 16 to the service tank 17 is regulated closely so as to maintain the liquid in the tank 17 constantly at the proper level. A simple and very effective means for maintaining the proper liquid level includes a port 53 (see Figure 10) in the tank 17 below the level of liquid in the tank 16, and a cooperating valve 54 carried by an arm 55 pivotally mounted on a bracket 56 and equipped with a float 57. Because of the low static pressure at the level of the port 53, the very simple and economical valve construction shown maintains a very delicate and exact control of the working level in the service tank 17.

Figures 11 and 12 show a modified form of cover 58 and top casing section 59 which may be used in place of the cover 14 and top section 5 described with reference to Figure 1. The modified top section 59 is similar to the section 5 previously described, with the exception that it is not formed with outlet openings corresponding to the openings 2 in the section 5. The modified top section 59 is, however, formed with an inwardly offset, upwardly extending flange 60 adapted to receive the downwardly extending flange 61 of the modified cover 58.

The cover 58 includes an outer annular part 62 from which the flange 61 depends, the part 62 in the main, however, extending at an inclination upwardly and outwardly from an inner, depending flange 63. Secured to the annular part 62 are three arcuate radial ribs 64 which serve to support concentrically arranged and spaced annular members 65 shaped similarly to the member 62, with the exception that they have no flanges corresponding to the flange 61. The ribs 64 also support a central member 66. The spacing and

concentric arrangement of the parts 62, 65 and 66 provide upwardly and outwardly diverging air outlet openings 67.

As shown in Figures 8 and 9, the caster-mounting equipments 6 comprise caster wheels 68 carried by vertical stems 69 mounted for turning and sliding movement in lugs or ears 70-71. Each stem 69 is urged upwardly by a spring 71 interposed between the lower lug or ear 70 and a pin 72 extending transversely through the stem 69. Thus, normally, the casters are in the retracted position shown in full lines in Figure 9, permitting the casing structure to rest firmly upon a floor.

In order that the casters may easily be moved to the dotted line position shown in Figure 9 for facilitating moving the unit, the upper end 73 of each stem 69 is arranged to cooperate with a cam 74 pivoted as at 75. The arrangement is such that when the cam is rocked counterclockwise from the position shown in full lines in Figure 9 to the position shown in dotted lines in this figure, the stem 69 is pushed downwardly against the urge of the spring 71 so as to move the caster wheel 68 to its extended or floor-engaging position.

Any suitable means may be provided for filling the main reservoir 16. In the form shown, a retractable filler spout or lip 76 is pivoted at 77 to the intermediate casing section 4. The arrangement is such that the spout 76 may be extended to facilitate pouring of water into the reservoir 16, and may then be retracted so as to merge with the general contour of the casing.

The construction shown embodies the invention in a preferred form, but it is intended that the disclosure of a preferred embodiment be illustrative rather than definitive of the invention. The invention is defined in the claims.

I claim:

1. A sectionally constructed portable air conditioning unit, comprising a bottom casing section including a tank for evaporative liquid; means carried by said bottom section for picking liquid up from said tank and discharging it in dispersed form above said bottom section; an intermediate casing section provided at its lower end with an inwardly offset, downwardly extending flange which fits inside of said bottom section, and with a horizontal shoulder which fits down on the top edge of said bottom casing section; air inlet openings in the lower part of said intermediate section; a throat member mounted in said intermediate section above said inlet openings; a series of vertically extending baffles carried by said throat member and extending downwardly past said inlet openings; a reticulated mat mounted within said intermediate section and supported removably on said throat member; a top casing section provided at its lower end with an inwardly offset, downwardly extending flange which fits inside of said intermediate section and with a shoulder which fits down on the top edge of said intermediate section, and provided at its upper end with an inwardly offset upwardly extending flange; air outlet openings in said top section; an inverted frusto-conical end section mounted within said top section with its base uppermost and secured to said top section immediately above said air outlet openings; a motor mounted on top of said end section and having a vertical shaft extending downwardly therethrough; a fan on said shaft below said end section; and a cover section having a vertical wall portion which fits

over the upwardly extending flange on said top casing section.

2. In air conditioning apparatus, a casing providing an air duct; means for moving air through said duct; an open top tank in said duct for containing evaporative liquid; rotatable means for dipping into said tank and picking up liquid and throwing it upwardly into said duct; and a horizontal disperser disk mounted for rotation about a vertical axis and having its bottom surface arranged as a target in the path of the liquid thrown by said rotatable means, said disk having a circular groove in its bottom, and slots open at the bottom leading from the groove to the periphery of the disk.
